INFANT'S DRESSING TABLE

Homer Arey, Salisbury, N. C.

Application August 16, 1950, Serial No. 11,786

Term of patent 14 years

(Cl. D33—14)

To all whom it may concern:

Be it known that I, Homer Arey, a citizen of the United States, residing at Salisbury, in the county of Rowan and State of North Carolina, has invented a new, original, and ornamental Design for Infant's Dressing Table, of which the following is a specification, reference being had to the accompanying drawing, forming part thereof, in which the single figure is a perspective view of an infant's dressing table, showing my new design.

The rear of the dressing table is plain.

I claim:

The ornamental design for an infant's dressing table, as shown and described.

HOMER AREY.
